UNITED STATES PATENT OFFICE.

JAMES SWEENEY, OF CORNING, OHIO.

CHURN-POWER AND BUTTER-WORKER COMBINED.

SPECIFICATION forming part of Letters Patent No. 328,906, dated October 20, 1885.

Application filed December 29, 1884. Serial No. 151,432. (No model.)

To all whom it may concern:

Be it known that I, JAMES SWEENEY, a citizen of the United States, residing at Corning, in the county of Perry and State of Ohio, have 5 invented certain new and useful Improvements in Churn-Powers and Butter-Workers; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 The object of this improvement is a churn-power having a spring, pawl and ratchet mechanism that can be applied to operating one or more dashers of a churn, either by short distinct applications of force or used to drive 20 the same continuously for a time, and by thus giving the operator intervals of rest relieve the labor and make the operation of churning less laborious. These results are attained by the means illustrated by the drawings here- 25 with as part hereof, in which the same letters of reference denote the same parts in the different views.

Figure 1 is a top view of a churn-power embodying the features of my improvement, with 30 sections broken away to better illustrate the construction and relative position of the parts. Fig. 2 is a side elevation of the same. Fig. 3 represents a longitudinal vertical section of the mechanism and the practical application 35 thereof to churning.

A is a supporting-base for the mechanism, and operates also as a lid or cover for the churn; B B', brace-beams transversely secured to the base A, and provided near each end 40 with round or square uprights D D', rigidly affixed in the position shown by any suitable means.

F are beams longitudinally connecting the uprights D D', to which they are affixed by 45 screws f', or otherwise.

E is a beam supported by and affixed centrally to the transverse brace-beams B B', for the purpose of supporting the gear-wheel G, loosely fitted to a shaft, G', which extends 50 through the beam E, as shown in Fig. 2, and through a disk affixed to the beams F by screws

f⁶, or otherwise, for the purpose of strengthening the superstructure, and also for the attachment of a coil-spring, f, having an eye, f², by means of which it is firmly affixed to the 55 disk F', and is connected there with the shaft G'.

F² is a ratchet wheel or plate rigidly affixed to the shaft G', but disconnected from the gear-wheel G.

F³ is a pawl suitably secured to an elevation 60 of or recess in the body of the gear-wheel G in position to engage with the detents in the ratchet-plate F², against which it is actuated by means of a spring, F⁴, affixed to the body 65 of the gear-wheel G.

F² is a plate secured to the shaft G' between the ratchet F² and the coil-spring f, for the purpose of preventing its entanglement with adjacent parts, and thus insuring its free action.

G³ is a knobbed lever for operating the mechanism hereinbefore described, as hereinafter more fully set forth.

C' C² are standards having laterally-extended bases c c' c², by means of which they 75 are affixed to the base A by screws or otherwise, for the purpose of supporting a shaft, H³, provided at its inner end with a pin-gear, H h, which meshes with the gear-wheel G, and at its outer end with a gear-wheel, P, which 80 meshes with a pinion, P', on a shaft, p, supported by standards C' C², and provided at its outer end with a blade, Q, having a recess, Q' q, for a purpose hereinafter set forth.

H' H² are gear-wheels supported by shaft 85 H, and provided with laterally-projecting teeth h' h², which mesh with pinions K K', secured to vertical shafting k k', supported by transverse frame-work composed of transverse beams N n N' n' and vertical standards N² N³, 90 affixed to the longitudinal bars M M', which are suitably secured to the base A. The lower ends of the shafts K K' are provided with square sockets L L, which fit over the correspondingly-formed upper ends of and connect the mechanism with the churn-dasher shafts S S'. (Substantially shown in Fig. 3.)

R R' R² R³ R⁴ represent the sides, ends, and bottom of the churn-box, suitably secured to the ends of which are vertical strips d d' at 100 each side of movable pieces d² d³, which are additionally held in the positions shown by

means of a movable bottom piece, d^4 , recessed at its ends to fit over the upright pieces d d' , as shown at d^5 , and by a longitudinal piece, R^5 , having perforations for the reception of the dasher-shafts S S' , and perforations at its ends for the reception of rounded ends d^6 of the movable uprights d d' , the object of said construction being to hold the dasher mechanism in proper relative position for use and to allow removal of the same for the purpose of thorough scalding and cleaning of the parts, as occasion may require.

S^2 S^3 S^4 are the dasher-blades. The dasher-shafts are provided with journals s , which fit into the correspondingly-perforated bottom piece, d^4 . By turning the operating-lever G^3 on the shaft G' the coil-spring f will be wound around the shaft G' , as shown in Fig. 1, and the pawl F^3 on the body of the gear-wheel G will be pressed into engagement with the ratchet-wheel F by the spring F^4 , and so connect the gear-wheel G with the spring f that when the lever G^3 is released the force of the spring will put the gear-wheel G in motion, and, by means of the meshing pin-gear H h , put in motion the gear-wheels H' H^2 , and drive the dashers through the pinions K K' continuously until the tension of the spring f is lost by being unwound, the process of which, because of the relative size of the gear G , pin-wheel H h , gears H' H^2 , and pinions K K' , will require

sufficient time to give the operator of the churn a period of rest; or the mechanism can be operated through short distinct applications of force by giving the lever G^3 only partial turns and reversing the movement thereof, which will actuate the gear G through the pawl F^3 , and thus give motion to the outer parts. 35

Having explained the construction and operation of my improvement, what I claim as 40 new, and desire to secure by Letters Patent, is—

1. The combination of the shaft G' , spring f , disk F' , ratchet F , gear-wheel G , provided with pawl F^3 , and pawl-spring F^4 , arranged to 45 operate substantially as described, for the purpose set forth.

2. The shaft H^3 , provided with the gearing H h , H' , H^2 , and shafting k k' , provided with sockets L and gearing K K' , in combination 50 with the gear-wheel G , arranged to operate as described, and the churn-dashers, for the purpose set forth.

3. The blade Q , having recess Q' q , arranged to operate as described, for the purpose set 55 forth.

In testimony whereof I affix my signature in presence of two witnesses.

JAMES SWEENEY.
